GAS HEATER

Harold W. Hart, Los Angeles, Calif.

Application June 1, 1936, Serial No. 82,681

7 Claims. (Cl. 126—85)

My invention relates more particularly to a type of gas heater which can be used as a portable heater and moved from place to place, or which can be permanently connected with the 5 gas supply in a room, and which stands above the floor in the manner of a stand lamp and so constructed and arranged that it develops a circulating heat current and also a radiated heat directed downwardly and outwardly toward the 10 floor area surrounding the heater.

Among other objects of my invention are: to provide in a gas heater of the character referred to, an improved burner, preferably in sections and related so as to function as a circular burner unit, 15 yet composed of a plurality of sections each of which receives its supply of gas and air and mixes it for combustion at the discharge outlet of the burner; to provide in connection with a gas burner an overhanging heat radiating element of refractory material of the radiant type and adapted to be heated by the combustion of the 20 gas mixture thereunder whereby to cause a definite radiation of heat downwardly and outwardly from said element or elements; to provide in a gas heater of the type referred to a construction and arrangement of hood or body which is kept cool around its outer surface, thus reducing any 25 danger to a minimum and preventing possibility of fire from contact of flammable material there- with; to provide in combination with a gas burner or heater of the character referred to an improved thermostatic control for regulating the gas supply to the burner according to a pre- 30 determined temperature which it is desired to maintain; to provide a gas heater of the character referred to having a supporting base casting of such weight relative to the top and body thereof that there is little or no chance of its being overturned from accidental contact therewith; to 35 provide a construction and arrangement which permits of its being disassembled into small compass for packing and shipping; and, in general, to provide an improved gas heater of the character referred to which is practical, efficient, 40 economical and ornamental.

In order to fully explain my invention, I have illustrated one practical embodiment thereof on the accompanying sheet of drawing, which I will now describe:

50 Figure 1 is a vertical sectional view taken through a gas heater embodying my invention;

Figure 2 is a bottom plan view, with parts broken away, taken on line 2—2, of Fig. 1;

Figure 3 is a fragmentary sectional view taken 55 on line 3—3 of Fig. 1; and

Figure 4 is a plan view looking down on the base or feet and the thermostat control, taken on line 4—4 of Fig. 1.

Referring now in detail to the drawing, I have shown a base casting 5, having the legs or feet, 5 6, 6, the top socket 7, and the dial supporting parts, 8, 8, with a dial 9 supported therein, with a revoluble dial indicator 10, on the upper end of a rod 11, threaded at its lower end through a bracket-like member 12, forming a part of a 10 thermostat, designated as a whole T.

Said thermostat T includes a casting 13, secured up under the base casting 5, with small screws, as at 14, and having therein two gas passages 15 and 16, leading to and from a chamber 17, formed by a diaphragm 18, provided in its center with a diaphragm gasket 19 positioned and adapted to close the passage 15 to said chamber 17, as shown. Supported immediately beneath said diaphragm 18 and adapted to engage 20 and move it is a thermostat wafer 20, attached at its under side to a lever 21, pivotally supported at 22 in the casting or bracket 12, with the outer end of said lever 21 positioned under the end of said threaded rod 11, as shown. A sheet metal 25 housing 23 encloses the parts of said thermostat, as indicated, said housing having the vent openings 23' around its lower end for temperature influence of the thermostat wafer. A gas supply pipe 24 connects with the gas passage 15, 30 and this pipe 24 can be either pipe or hose, as desired.

Screwed into the thermostat casting 13, is a vertical pipe 25, jointed at 26, to permit its being taken apart. This pipe communicates with the 35 gas passage 16 in the casting 13, as indicated. A tubular shield 27 is placed down over the pipe 25 and seated in the socket 7 in the base casting 5, as shown. The upper end of the tubular shield 27 has seated thereon a cap 28, with opening 40 therethrough for the gas pipe 25, and it also is formed to receive the lower end of an upper tubular shield 29, as indicated. Into the upper end of the tubular shield 29 is fitted a tapering collar 30, screwed on the upper end of the pipe 25, and 45 operating to force the tubular shields 27 and 29 into rigid relationship with each other and with the base casting 16, and giving rigidity to the supporting structure and the base.

Placed over the upper end of the gas pipe 25, 50 is a cup-like casting 31, fitting down over the collar 30, and having formed thereon three supporting arms, 32, 32, 32, for supporting the reflector 33, and the outer shade or ornamental body 34, said reflector 33 and outer shade being separated 55

by a spacing clip 35, fitted down upon the up-turned bead-like edges of said reflector and shade, and held in place by a screw bolt 36 up through the outer ends of the arms 32.

5 Screwed down upon the top of the casting 34, is a triangular casting 37, having its center open to receive the tapered screw end of the gas pipe 25, and having gas passageways extending 37' outwardly through its three arm portions, as 10 seen in Fig. 2, and also in Fig. 1. The outer ends of said arm portions are shown upturned or provided with jet nozzles, as at 38, and are formed to receive each a burner section 39, held in place thereon by small screws 40. The burner is really 15 three burners, or burner sections, in one unit, with three separate Venturi tubes 39, each receiving the gas jet at 38, and having in its upper part a projecting baffle lip 39' in its head portion, designated 41. The upper end of each head 20 portion 41 is provided with transverse discharge slots 42, at which the combustion takes place around the full circle of the three burner bodies, as shown.

25 Supported by means of small brackets, 43, to the inner middle part of the reflector 33, is a hollow shell-like structure 44, providing air space insulation above the burner. Suspended under this shell member 44, by a bolt 45, is a supporting member 46, having its outer edge formed to support the lower ends of radiant elements 47, the 30 upper ends or edges of which are supported by means of struck-out lips 48, around the outer edge of the lower member of the shell 44. Said radiant elements are of segmental form and when 35 placed together form a conical surface with the usual small projections 47' on their overhanging surfaces. Supported around the burner head 41, upon the arms 32, is a wire screen 49, for safety against any falling part and for protecting 40 the open flame from children.

45 As a result of a great deal of experimental work, I have worked out a construction and arrangement of the several parts of my heater so as to get the proper amount of heat radiated downwardly and outwardly and the proper amount of heat going up through the heater and creating a circulating current of heat, and also the reflected heat from the reflector. Consequently 50 my heater can be placed near furniture, close to a wall or even against lace curtains without any danger therefrom. The screen 49, not only serves as a protection from the possibility of any of the radiant elements falling out of place, and as a protection to prevent children getting to 55 the flame, but the screen is an important factor in preventing too much heat being radiated downwardly.

60 The reflector 33, which is preferably made of aluminum, is placed at just the proper angle to reflect the heat outwardly in all directions and to the body of a person sitting close to the heater, thus making for comfort. The outer shade or body 34 is so placed with an inch or more space for air between it and the reflector 33, that said outer shade 34 is always cool. The insulating shell 44 above the burner and the radiant segments prevents too much heat from passing upward through the center of the heater, and although a curtain or other article might be blown over the top of the heater, it will not be 65 burned or damaged.

70 The base casting structure is sufficiently heavy relative to the top part of the heater that it will right itself even though it be tilted to an angle of 25 degrees, and even though knocked over

7 on its side, it is not a fire hazard for the reason that the burner is of the Bunsen type, is fastened securely and will remain burning evenly.

5 By providing the large hole through the center of the sectional burner and enough distance between the burner and the radiant elements, the air will circulate around the burner from all sides and up through the center to allow the best mixture and most perfect combustion.

10 The thermostat, being protected under the base, is not subject to the radiated heat, but is positioned where the cool air is always more noticeable near the floor and where it will function more effectively to regulate the temperature of the room according to the desire of those using it 15 and it can be set to function automatically to maintain a predetermined temperature.

1 A aware that changes in the general construction and arrangement of my improved heater can be made without departing from the 20 spirit thereof, and I do not, therefore limit my invention to the embodiment thereof shown and described, except as I may be limited by the hereto appended claims.

25 I claim:

1. A gas heater including in combination a base, a gas supply pipe having its lower end anchored in said base and standing upright like a stand lamp, a gas burner mounted on the upper end of said pipe, a heat radiating member of inverted conical form supported by said pipe centrally above said burner and adjacent thereto, whereby to be directly heated thereby, and a surrounding shade supported by said pipe at its upper end around said burner for reflecting 35 radiated heat from said radiating member.

2. A gas heater including in combination a base, a gas supply pipe having its lower end anchored in said base and standing upright like a stand lamp, a gas burner mounted on the upper end 40 of said pipe, a heat radiating member of inverted conical form supported by said pipe at its upper end centrally above said burner and adjacent thereto to be directly heated thereby, a shield immediately above said heat radiating member, and a double wall shade surrounding 45 said heat radiating member and said shield and supported by arms from the upper end of said gas supply pipe, whereby said gas heater has the appearance of a stand lamp with shade.

3. A gas heater including a base to stand upon the floor, a gas supply pipe anchored at its lower end to said base and extending upwardly therefrom, tubular finishing means around said pipe, a gas burner mounted upon the upper end of 55 said gas supply pipe, a heat radiating member immediately above said burner to be heated thereby, a shade surrounding said radiating member for reflecting radiated heat downwardly, said heat radiating member and said shade being supported by the upper end of said gas supply pipe and the tubular finishing means, a guard screen around said burner, within said shade and under said heat radiating member, and means in said base for connecting a gas supply to said gas 60 supply pipe.

4. A gas heater including a base, a tubular member anchored at its lower end to said base and standing upright like the standard of a stand lamp, a gas pipe connected to said base 70 and extended up through said tubular member, means for connecting a gas supply to said gas pipe underneath said base, with valve means therefor, a gas burner mounted on the upper end of said gas pipe, supporting arms from the upper 75

ends of said gas pipe and said tubular member extending outwardly and upwardly and having supported thereon a shade surrounding said gas burner, said shade having a double wall, a heat 5 radiating member of inverted conical form having its central small end centrally above said gas burner to be directly heated thereby, a screen around said burner and under said heat radiating member, and a shield directly over said heat 10 radiating member within said shade.

5. A gas heater having a vertical support supporting it above the floor like a stand lamp, a gas supply pipe leading thereto, a base supporting said pipe and said heater, said base having 15 a shield portion, a thermostat connected into said gas supply under said base shield portion to be sheltered thereby from downwardly directed heat from said heater, whereby to automatically regulate the gas supply, means for adjusting said thermostat to predetermined temperature marks, and a heat reflecting member associated with said heater for directing heat 20 downwardly toward the floor.

6. A gas heater including a vertical stand pipe, 25 a base member supporting said pipe and having a shield portion, and having means associated therewith for connecting a supply of gas to said pipe, a thermostat control mechanism under said base shield portion and connected into said gas

supply for automatically regulating the flow of gas, said thermostat mechanism being covered by the shield portion of said base, whereby to shelter it from radiated heat from said heater, a burner at the upper end of said pipe, and a heat radiating member mounted adjacent said burner to be heated directly thereby, whereby to 5 radiate heat downwardly and outwardly.

7. A gas heater of stand lamp form including a base, a gas supply pipe anchored at its lower end in said base and standing upright, a burner mounted on the upper end of said pipe, a heat radiating member mounted directly above said burner and overhanging the same at an angle between the vertical and the horizontal, whereby 10 to be directly heated from said burner, a shade around said heat radiating member and forming a guard and reflecting means for deflecting heat downwardly, said heat radiating member, said shade and said burner being supported from the upper end of said gas supply pipe by arms 15 radiating outwardly therefrom, and thermostatic control mechanism connected into said gas supply pipe, under said base and shielded by a part of said base from radiated heat, whereby the 20 temperature at the floor controls said thermostat mechanism.

HAROLD W. HART.
